OIL THIEF AND SAMPLER

William L. Walker, Tulsa, Okla.

Application February 26, 1938, Serial No. 192,873

9 Claims.

(CL. 137—18)

The invention relates to oil thieves or samplers used for obtaining spot samples from different depths in an oil storage tank, and from the bottom of the tank for testing purposes, and has for its object to provide a device of this character adapted to be lowered through the theft hole of the tank by a supporting member and provided with an open spring closed valve, which may be released at any depth desired by a jerk on the supporting means, for obtaining a sample from any predetermined depth.

A further object is to provide the thief with a spring closed valve, laterally movable at its lower end, and cooperating with a seat at the lower end of the casing in a manner whereby, as the valve reaches its closed position, the valve is moved upwardly towards the seat for insuring a positive seating and preventing wear on the valve and seat, particularly when taking a sample from the bottom settlement, which contains abrasive material, thereby preventing wear on the parts.

A further object is to rockably and rotatably mount the disc valve on the valve arm thereby insuring a positive seating of the disc valve on the valve seat at all times.

A further object is to hingedly mount the valve arm within a tripping mechanism to one side of the thief cylinder, and to provide the tripping mechanism with a detent releasing finger cooperating with the arm for holding the arm and its valve in open position against spring action until the tripping mechanism is operated for a valve closing operation.

A further object is to provide means whereby the valve and valve arm, as they move towards closed position, are in a plane below the plane of the valve seat, and as they approach the closed position they are moved upwardly to seated position towards the seat, obviating cutting and scoring of the valve and valve seat incident to particles in the bottom settlement.

A further object is to provide a downwardly adjustable tripping rod which may be adjusted to various positions for tripping the valve at various distances from the bottom of the tank.

A further object is to provide the upper end of the casing with a bail having a bell crank connected thereto and extending outwardly and downwardly to one side of the device and attached to the tripping mechanism whereby the tripping mechanism is released when a jerk is imparted on the supporting line attached to the bell crank lever for releasing the valve at predetermined depths.

A further object is to provide the valve arm

with an upwardly extending sleeve rotatably mounted in a stationary sleeve to the side of the casing and anchored to an adjuster head, rotatably mounted in the tripping mechanism casing, and a torsion spring within the casing and connected to the casing sleeve for normally forcing the arm and its valve towards closed position.

A further object is to provide a vertically movable tripping sleeve having a stationary head thereon to one side of the main casing, and provided with a releasing rod which cooperates with the valve arm and an aperture therein for holding the valve arm in open position until the tripping rod is actuated.

A further object is to utilize the tripping mechanism spring for forcing the valve and its arm upwardly as it approaches closed position, and spring means whereby the releasing tension can be varied.

A further object is to provide sample test cocks on the side of the casing so samples may be taken therefrom for test purposes.

A further object is to provide a slidable open sided hydrometer windshield which may be extended upwardly for protecting the hydrometer during the testing operation.

A further object is to provide the inner side of the windshield with a channel for holding a graduated water and bottom settlement gauge.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a perspective view of the sampler.

Figure 2 is a vertical longitudinal sectional view through the sampler.

Figure 3 is a horizontal sectional view taken on line 3—3 of Figure 2.

Figure 4 is a bottom plan view of the sampler showing the valve closed.

Figure 5 is a view similar to Figure 4 but showing the valve open.

Figure 6 is a side elevation of the sampler showing the valve closed.

Figure 7 is a view similar to Figure 6, but showing the valve open.

Figure 8 is a perspective view of the valve carrying arm and its pivot sleeve.

Figure 9 is a vertical transverse sectional view through one side of a conventional form of storage

tank, showing the device suspended therein ready to be tripped by the trip rod engaging the bottom of the tank.

Figure 10 is a side elevation of the upper end of the main casing showing the windshield extended.

Figure 11 is a perspective view of the water and bottom settlement gauge.

Figure 12 is a top plan view of the windshield. Referring to the drawings, the numeral 1 designates a portion of a conventional form of oil storage tank, and 2 fluid therein. The thief or sampling device is lowered through a conventional form of thief or man hole, and fluid at different depths is trapped therein and raised from the tank to a point where the contents thereof can be tested for settlement, temperature and the like.

The sampling device comprises a cylinder 3 having a chamber 4 therein, and in which the oil is trapped and raised to the top of the tank. Secured to the bottom of the cylinder 3 is a bottom ring 5, which carries the valve structure and tripping mechanism hereinafter set forth and secured to the upper end of the cylinder is a top ring 6, preferably provided with a pouring lip 7 for facilitating the pouring of the contents from the sampler during testing operations. Ring 6 is provided with a pivoted support dog 8 so the device may be supported on the theft hole ring or man hole during the testing operation, or when desired. A second pivoted dog 9 is provided on the cylinder 3, and adjustable thereon by means of a split ring 10 for allowing the device to be supported on a different type or size of man hole ring if desired, and the upper end of the device higher than the tank if desired. Supporting dogs 8 and 9 are preferably provided with limiting lugs 11 so they will not pass outwardly beyond an acute angle, hence the device will be prevented from slipping from the supporting ring.

Pivoted at 12 to opposite sides of the ring 6 is a split bail 13, between the lugs 14 of which is pivoted at 15 an outwardly and downwardly extending trip arm 15a, which controls the tripping mechanism when a pull is imparted on the line 16 at a predetermined depth within the storage tank 1. Line 16 is preferably provided with a plurality of enlargements 17 so the operator will know how far the sampler is submerged and when to trip the same for getting a sample at any particular depth. The arm 15a terminates in a hook 18, which is received within an eye 19 carried by the vertically movable tripping sleeve 20, which is slidably mounted in a bearing 21 of the upper ring 6 and extends axially through a tension adjusting sleeve 22 having an expansion spring 23 therein, which is interposed between the ring 6 and the adjusting sleeve 24.

By adjusting the sleeve 24 through the medium of the set screw 25 on the trip sleeve 20, the amount of power necessary for the tripping action may be varied from a slight jerking motion to a heavy one.

The lower ring 5 is rigidly mounted on the lower end of the cylinder 3 and is provided with an annular valve seat 26, with which a pivotally and rockably mounted disc valve 27 cooperates. The disc valve, in its movement from open to closed position, moves in a plane downwardly spaced from the seat 26 so there is not a sliding engagement with the seat, which causes wear thereon, and as it approaches axial relation with the cylinder 3, there is a slight upward seating move-

ment, hence it will be seen there is no drag over the seat. Formed integral with the ring 5 is a tripping mechanism sleeve 28 having a combination torsion and compression spring 29 therein. The lower end of the spring 29 is anchored at 30 in the bottom of the sleeve 28 and has its upper end anchored at 31 in an adjuster head 32, rotatably mounted on the lower end of the trip rod sleeve 20 and on the upper end of the valve arm sleeve 33, which extends axially through sleeve 28 and the torsion spring 29. It will be noted that the compression spring 29 under longitudinal compression normally forces the adjuster head 32 upwardly and raises the valve arm 34, carried by the sleeve 33, hence it will be seen that the valve will be moved towards the seat 26 when released for upward movement. Adjuster head 32 is provided with set screws 35 for rigidly holding the same in adjusted position on the valve arm sleeve 33 and by adjusting these screws and rotating the head 32, the desired amount, the torsional tension of the spring 29 may be varied. Rigidly mounted at 36 on the trip rod sleeve 21 is a member 37 which carries the trip rod 38. Trip rod 38 extends downwardly through a guide bearing 39 in the lower end of the sleeve 28 and through an enlargement 40 thereof, which is outwardly offset so the rounded end 41 will ride on the cam flange 42, carried by the pivoted end of the valve arm 34.

Tripping rod 38 is normally urged downwardly by the expansive action of the spring 23, which may be adjusted through the medium of the adjusting sleeve 24 for a relatively light tripping or a heavy one. It will be noted that the disc valve 27 is rockably and rotatably connected to the arm 34 at 43 for the seating operation of the valve on the seat 26, consequently the valve will seat under all conditions.

When the device is lowered into the tank, the valve is in open position as shown in Figure 5, and at which time the lower rounded end 41 of the rod 38 is disposed in the aperture 44 of the horizontal portion 45 of the cam member 46, carried by the valve controlled arm 34, hence the valve is held in open position as shown in Figure 5. When the device is tripped, for instance upon a jerk on the control line 16, the trip controlled sleeve 20 is pulled upwardly, and as the member 37 is rigidly carried thereby, the trip rod 38 will move upwardly therewith, out of interengagement with the aperture 44. The spring 29 then rotates the adjusting head 32 carried by the sleeve 33 of the valve arm 34 and the valve and arm are moved towards closed position with the portion 40 in engagement with the extension 46 of the arm. As the valve approaches closed position, the portion 40 will ride on the inclined portion 47 of the cam 46, and the arm is moved upwardly by the spring action so the valve will suddenly seat at the closed position. To further insure a positive seating the under side of the valve carrying arm 34 is provided at its free end with a cam surface 48, which engages the roller 49, carried by the arm 50 of the lower ring 5, hence it will be seen there is no spring action to the arm and there will be a positive seating and holding of the valve against the seat.

Axially adjustable within the trip rod sleeve 20 is a bottom trip rod 51, the upper end of which is bifurcated as at 52 to form spring arms for frictionally engaging the inner periphery of the sleeve 20 and holding the rod against displacement during the adjustment thereof. Rod 51 is provided with graduations so the operator can

tell how far its headed end has been extended below the device and for tripping the device at a predetermined distance from the bottom of the tank, for instance when samples of the bottom settlement are desired. After the rod 51 has been properly adjusted, it is held in adjusted position by means of a set screw 54, preferably of the thumb type, which is threaded through the member 37 and sleeve 20 and jams against the rod 51, thereby rigidly holding the same. When the headed member 53 engages the bottom of the tank with the valve in open position, the rod 51 is forced upwardly along with the sleeve 20, member 37 carried thereby and latching rod 38, and at which time the valve arm 34 and valve carried thereby swing in a lateral plane in spaced relation to the valve seat while the member 40 is riding on the high portion of the cam member 48. When the arm and valve approach the closed position the portion 44 rides down the cam portion 47 to the low portion 55 of the cam under the influence of the spring 29, which has been compressed during the adjustment of the tension of the spring through the adjusting head 32. The outer end cam 48 of the valve arm engages over the roller 49 for insuring a positive seating operation on the valve seat 26. Arm 34 is preferably provided with a finger engaging member 56, adapted to be grasped by the operator for returning the valve to open latched position for the next sampling operation.

Telescopically disposed and frictionally held within the cylinder 3 is a cylindrically shaped windshield 57 having a vertical opening 58 there-in. The upper end of the windshield is provided with a lip 59 which engages over one side of the upper ring 3 for limiting the downward movement of the windshield and forming a handle adapted to be grasped by the operator for extending the windshield so a hydrometer reading may be taken within the same. Slidably and removably mounted between retaining strips 60 on the inner periphery of the windshield 57 is a water and bottom sediment guage 61, which is adapted to be removed for taking a water or bottom sediment reading. Usually, when the water reading is taken, the guage 61 is provided with a cork coating which is saturated by the water. Guage 61 is provided with a lip 62 which overlies the lip 59 of the windshield, and the operator can easily remove the guage 61 by grasping the lip 62 and imparting an upward pull thereon.

When the windshield is used, the hook 18 is removed from the eye 19, and the bail 13, along with the arm 15, is swung outwardly to the position shown in Figure 10, thereby allowing the windshield to be easily raised. The suspension line 16 is preferably provided with a hook 63, which hooks into an eye of the angular member 15a.

From the above it will be seen that a sampling device is provided, by means of which samples of oil may be taken from different depths in the tank, and the valve is mounted and operated in a manner whereby it will positively seat at the closing point, and the valve, being rockably and rotatably mounted, will properly seat in different positions incident to successive operations, and will practically regrind the seat as it is used from time to time.

The arm 34 and bottom ring 5 are provided with legs 64, which in combination with the arm 50 forms supporting means for the device when not in use.

It will be seen that the sampling device is so

constructed that it has no bail holes in the top and can be used as a sample jar thereby eliminating same for taking gravity. The bail is so constructed that the thief hangs perpendicular when not using the jerk mechanism, part 51; also the springs are enclosed so they will not fill up and foul in heavy bottom settlement and sand.

The tension of the springs can be easily adjusted to suit the operator, and the closer tube head, part 19 is offset so a long rod will pass through the trip mechanism. This offset 19 permits a longer rod to be inserted at the top, and it is then possible to take a sample, for instance six feet from the bottom by means of a seven foot trip rod.

The invention having been set forth what is claimed as new and useful is:

1. A sampling device comprising a receptacle adapted to be lowered into a body fluid for trapping fluid at various levels, said sampling device comprising a receptacle having an open lower end surrounded by a valve seat, a laterally movable valve cooperating with said seat, an arm on which said valve is mounted, a pivot sleeve carried by said arm and pivoted to one side of the receptacle, spring tension means cooperating with said arm for normally moving the same to closed position, a vertically slidably detent to one side of the receptacle and cooperating with the arm for holding the same in open position and lowering means in connection with said detent means for releasing the same at predetermined depths to allow the arm and its valve to move to closed position under the influence of its spring means.

2. A device as set forth in claim 1 including spring means for normally maintaining the detent means in holding position.

3. A device as set forth in claim 1 including cam means carried by the arm and receptacle for holding the valve in a different plane from the seat during its initial closing movement and seating said valve on its final movement.

4. A sampling device comprising a receptacle having its lower end open, a valve seat carried by the receptacle around its open end, a pivoted arm below the seat, an upwardly extending tubular stem carried by the pivoted arm to the side of the receptacle, a casing through which said tubular stem extends and in which it is rotated, spring torsion means within the casing and cooperating with the upwardly extending tubular stem for normally forcing the same and the valve carrying arm to closed position, a valve carried by the valve arm and cooperating with the seat, said spring also being compressed to impart an upward axial movement to the upwardly extending arm, a tripping member above the upwardly extending arm, a detent member carried by the tripping member and cooperating with an aperture in the valve arm for holding the same in open position and cam means cooperating with the valve arm whereby upon its initial movement to closed position it will move in a plane spaced from the valve seat and on its final movement will force the valve to seating position.

5. A fluid sampling device adapted to be lowered into a body of fluid comprising a receptacle having a fluid inlet, a valve mounted on the receptacle and adapted to be moved to closed and open relation to the inlet, a latch cooperating with the valve for retaining the valve in open position, a tripping device for releasing the latch and allowing the valve to move to closed

position, a bail carried by the receptacle, a bell crank carried by the bail, lowering means connected with the bell crank, and means connecting said trip with the bell crank for release of the trip upon an upward jerk of the lowering means.

6. In a fluid sampling device adapted to be lowered into a body of fluid, the combination with an open-bottom receptacle having a valve seat, an exterior sleeve rigid with the receptacle, and an open center cap closing the upper end of said sleeve, of a horizontal valve-arm having a tubular upright stem concentric with the sleeve and oscillatable therein, said valve arm also being movable in a vertical plane, a valve adapted to close the seat, said valve being loosely mounted in the valve arm and having a central bearing thereon, a combined torsion and compression spring having its respective ends fixed to said cap and to the bottom portion of the sleeve, means whereby the valve-arm and valve are set in open position, and means for releasing the valve arm whereby the valve closes its seat.

7. The combination with an open-bottom receptacle having a valve-seat, an exterior sleeve rigid with the receptacle, and an open-center cap covering the upper end of said sleeve, of a horizontally movable valve-arm having an integral upright stem concentric with the sleeve and oscillatable therein, adjustable means for securing the cap to the stem, said valve arm also being movable in a vertical plane to and from said seat, a valve adapted to close the seat, said valve having a central bearing member and loosely mounted on the arm, a combined torsion and compression spring having its respective ends fixed to said cap and to the bottom portion of the sleeve, means whereby the valve arm is swung laterally to set position, and means for releasing the valve arm from set position to permit the valve to close said seat.

8. The combination with an open-bottom re-

ceptacle having a valve seat, an exterior sleeve rigid with the receptacle and an open-center cap closing the upper end of the sleeve, a horizontal valve arm having a tubular upright stem concentric with the sleeve and oscillatable therein, said valve arm also being movable in a vertical plane, and a valve having a hemispherical bearing member mounted in a seat on the valve arm, of a combined torsion and compression spring joining said cap and the valve arm, a spring 10 projected trip rod with its lower end telescoping said cap and stem, a trip-pin forming a co-planar extension of the rod, an exterior flange at the base of the tubular stem having in its upper face a hole to receive the pin and retain the 15 valve in open position, and means for actuating the trip rod to release the pin.

9. The combination with an open-bottom receptacle having a valve-seat and an exterior sleeve, an open-center cap closing the sleeve, a 20 horizontally movable valve arm having a tubular upright stem concentric with and oscillatable in the sleeve, said arm also being movable in a vertical plane, and a valve having a central bearing member loosely mounted on the valve arm, 25 of a combined compression and torsion spring uniting said cap and valve arm, a spring projected trip-rod with its lower end telescoping said cap and stem, a trip-pin forming a co-planar extension of the rod, an exterior flange at the 30 base of the stem having in its upper face a hole to receive the pin to retain the valve in open position, said flange also having a surface below said upper face in the path of the pin to receive the pin when the valve is closed, an inclined 35 surface connecting the upper face of the cam and surface therebelow and over which the pin rides, means for actuating the trip rod to release the pin from said hole, and co-acting means on the valve arm and a member mounted on the receptacle for elevating the valve to its seat. 40

WILLIAM L. WALKER.
